UNITED STATES PATENT OFFICE.

WALTER H. COTTON, OF CHICAGO, ILLINOIS.

ELECTRICAL IGNITING APPARATUS.

1,101,256.

Specification of Letters Patent. Patented June 23, 1914.

Application filed July 5, 1907. Serial No. 382,257.

To all whom it may concern:

Be it known that I, WALTER H. COTTON, a citizen of the United States, and resident of Chicago, county of Cook, and State of Illinois, have invented certain new and useful Improvements in Electrical Igniting Apparatus, of which the following is a specification, and which are illustrated in the accompanying drawings, forming a part

10 thereof.

This invention relates to electrical igniters for internal combustion engines of the type forming the subject matter of Letters Patent No. 735,213, granted to me Au-

15 gust 4, 1903.

The object of this invention is to generally improve devices of this kind, having reference to its application in connection with either the so-called make and break

20 type or the jump-spark type of ignition device, and to means for cleansing and increasing the certainty of action of the igniter.

The invention consists in the structure hereinafter described, and which is illus-

25 trated in various forms in the accompanying drawings, in which—

Figure 1 is a detail plan view of the ignition device as applied to a gas engine, one wall of which is shown in detail section;

30 Fig. 2 is a detail section on the line 2—2 of Fig. 1; Fig. 3 is an elevation of the inner face of the igniter casing; Fig. 4 is a sec-

35 tional detail of the igniter casing showing the valve; Fig. 5 is a detail, partly in sec-

40 tion, of an induction pipe used in connec-

45 tion with the device; Fig. 6 is a side eleva-

tion of the igniter showing a modified form

50 of construction; Fig. 7 is a sectional detail

of an engine and the igniter, showing a fur-

ther modification; Fig. 8 is a sectional view

55 on the line 8—8 of Fig. 7; Fig. 9 is an end

elevation of the igniter casing shown in

Figs. 7 and 8, but drawn to a smaller scale;

Fig. 10 is a sectional detail on a plane per-

55 pendicular to the plane of Fig. 8, showing,

however, a slight modification; and Figs.

11, 12 and 13 are details of the circuit

breaker.

The igniting device comprises a casing 10,

50 cored to form a chamber for the circulation

therethrough of water, while leaving stock

within the interior, as shown at 11, 12 and

13, for receiving the sparking elements, and providing suitable passages, as hereinafter described. Ports 14, 15, are formed in the 55 inner face of the casing, opening to its water chamber, and adapted to communicate with the water chamber 16 of the gas engine cylinder 17, to the outer wall of which the casing 10 is adapted to be secured by screw- 60 bolts 18.

A pair of plugs 19, 20, are set within suitable apertures within the interior metal parts 11, 12, and entering through the top of the casing. Each of these plugs carries 65 a pair of electric terminal rods 21, 21^a, and 22, 22^a, each of the latter being stationary and insulated from the plug, and each of the former being an oscillating spindle carrying a hammer 23, 23^a, at its inner end adapted for contact, respectively, with the inner end of the rods 22, 22^a, to close the electric circuit. Space is left below the plugs 19, 20, to accommodate the contacting parts of the terminals and provide chambers 24, 25, 70 within which the gases are to be ignited. These chambers communicate with the interior of the cylinder through a port 26 in the wall of the latter and a duct 27 through a valve 28 seated in a suitable aperture 80 within the metal part 13 of the casing, the duct 27 of this valve opening laterally through its body and registering in alternation with ports 29, 30, communicating with the chambers 24, 25. A handle 31 is at- 85 tached to the stem of the valve 28, by means of which the latter may be turned to bring one of the chambers 24, 25, into and cut the other off from communication with the chamber of the engine cylinder. A con- 90 nector 32 unites the two fixed terminals 22 and carries a binding post 33, to which one branch of the electric circuit 34 may be secured. The spindles 21, 21^a, are grounded 95 in the engine.

The oscillation of the spindles 21, 21^a, is accomplished in any desired manner. As shown, there is mounted loosely on the outer end of each of the spindles 21, 21^a, a shouldered disk 35, 45. The construction of 100 the two sparking appliances being alike, but one need be described in detail. A helical spring 36 is attached to the disk 35 and to the plug 19, and normally holds the spindle

in such position that the hammer 23 is out of contact with the rod 22, and bears against a suitable stop 37. A collar 38 is fixed upon the spindle 21 between the disk 35 and the 5 end of the plug 19, and a helical spring 39 has one of its ends secured to this collar and the other in the end of the plug. The two springs 36 and 39 exert their pressure in opposite directions, the spring 39 being 10 the weaker of the two. The collar 38 is provided at its upper end with a segmental flange 40, and the disk 35 has formed on its lower face a depending lug 41, playing between the ends of this flange, these parts 15 being so disposed that under the influence of the spring 36 the hammer 23 is thrown back against the stop 37 by reason of the engagement of the lug 41 with the flange 40. A reciprocating rod 42, mounted in suitable 20 slideways carried by a pair of brackets 46, 47, rising from the casing 10, carries a pair of yieldingly mounted fingers 43, 44, adapted to coat one with the disk 35 and the other with the corresponding disk 45 25 carried by the companion sparking device. As the rod 42 is advanced, one of the fingers engages the shoulder of the disk with which it cooperates. Assuming that the finger 43 is in action, it will engage the shoulder of 30 the disk 35, turning it and releasing the segmental flange 40, permitting the spring 39 to throw the hammer 23 into contact with the terminal 22. As the rod 42 still farther advances its finger slips past the shoulder of 35 the disk. Under the influence of the spring 36, the disk is now thrown backward to its normal position, carrying with it the collar 38 and the hammer 23, thus making a quick break of the electric circuit and developing 40 the igniting spark.

One of the bearings of the rod 42 is in the form of a sleeve 48, set through the eye of the bracket 47, and secured by means of a nut 49. This sleeve carries a spline 50, fitting within a longitudinal groove 51 in the rod 42, and is also provided with a radial stud 52, playing in a cam-slot 53 in one arm of a bell-crank 54, pivoted to a bracket 55 projecting from the casing 10. A segmental 50 flange 56, fixed upon the stem of the valve 28, engages by its shoulders a stud 57 on the outer end of the free arm of the bell-crank 54. As the bell-crank is turned on its pivot the sleeve 48, and with it the rod 42, are 55 turned by the action of the bell-crank cam on the stud 52. The two fingers 43, 44, are out of alignment, and the shoulders or ends of the segmental flange 56 are so spaced and disposed that as the valve 28 is turned to 60 open communication between the engine cylinder and either of the chambers within which the sparking devices are located, the rod 42 is so turned as to bring one of the fingers 43, or 44, into position to engage the 65 corresponding shouldered disk 35 or 45.

The rod 42 is reciprocated by the engine, and a connecting rod 58 leading from a clip 59 on the rod may be so connected to a moving part of the engine as to actuate the rod and suitably time the ignition of the charge 70 in the engine cylinder. The fingers 43, 44, may be attached to the rod in any suitable manner. As shown, they are pivoted within longitudinal apertures in the rod, and each is acted upon by a spring 60, 61, holding it 75 in position for engagement with the shoulder of the disk with which it cooperates but allowing it to yield for easy disengagement therefrom.

Preferably each of the ignition chambers 80 within which the sparking electrodes are located, is enlarged in order that as each new charge of the engine is compressed it may with certainty be forced past the sparking terminals. As shown, this is accomplished by forming ports 62, 63, leading one from each of the chambers 24, 25, through the wall of the casing 10, and attaching to the casing, so as to register with each of the ports, a tube 64, 65, having its outer end closed. To facilitate the cleaning of these tubes the outer end of each may be closed by means of a scavenger valve, as 66, seated in the open end of the tube and carried by a yoke 67, within which its stem is in threaded 90 engagement, such stem being provided with a hand-wheel 68 for its easy manipulation. Should the tube become foul the valve may be opened to permit the exploding charge 95 to blow out the accumulated material. 100

In Figs. 7 and 8 there is illustrated a modification, wherein the spark developing devices are located in pockets 69, 70, formed within a casing 71, similar to the casing 10, and opening to the chamber of a rotative valve 72, which is ported through its inner end, as shown at 73, to a port 74 in the wall of the cylinder 17. The chamber of the valve 72 is closed on one side, as shown at 75, thereby providing for the cutting off of 110 one of the pockets 69 or 70. The sparking device may be of any desired form, as illustrated jump spark plugs 76, 77, of ordinary construction, are employed, and if desired a plurality of such plugs may be inserted into 115 each of the pockets 69, 70, as illustrated in Fig. 10. A simple and efficient means for leading current to the sparking devices is shown, and consists of a binding post 78, mounted on the casing 71, and connected with a brush 79, bearing upon a metal ring 80, carried by a disk 81 of non-conducting material fixed upon the stem 82 of the valve 72. An arm 83 leads from the ring 80, and makes contact, in alternation, with contact 120 plates 84, 85, secured to the sides of the casing 71, and being connected with the plug or plugs 76, 77. The handle 86 of the valve 72 is so disposed relatively to the arm 83, that as the valve is thrown to either of its 125 130

extreme positions the circuit is closed to the 5
sparking device or devices located within the open pocket 69 or 70. To make it positively certain that combustible gases will
surround the sparking points, the induction
may be so arranged that the incoming
charge will sweep these points. This may
be accomplished, as illustrated in Figs. 7
and 8, wherein the induction passage 87
10 opens to a port 88 in the casing 71, which is
in communication with the chamber of the
valve 72, an inwardly-opening valve 89 be-
ing seated across the duct 87. Furthermore,
the throat 90 of the chamber of the valve 72
15 may be somewhat contracted, forcing the
charge into the open pocket 69 or 70. This
sweeping of the contact points by the incom-
ing charge may, however, be provided by
substituting for the tubes 64, 65, a tube 91,
20 the outer end of which is in communication
with the induction passage, thereby shunt-
ing a part of the incoming charge through
the igniting chambers, as 24, 25. When this
construction is followed the tube 91 should,
25 of course, contain a check-valve to prevent
firing back. This is shown as taking the
form of a ball 92, seated within an enlarged
chamber 93 in the tube and limited in its
movement by a stop pin 94.

30 I claim as my invention—

1. In an igniting device, in combination, a
combustion chamber, a valve casing open
thereto and having lateral pockets in its
35 valve chamber, electric sparking devices in
the pockets, a valve seated in the valve
chamber and having an axial and a lateral
port, a circuit breaker connected with the
valve and arranged to open the circuit of
40 each sparking device when the lateral valve
port is out of register with the pocket in
which it is located.

2. In an igniting device, in combination, a
combustion chamber, an igniting chamber
communicating therewith and having a fluid
45 induction port other than its opening to the
combustion chamber and having pockets in
its walls, an electric sparking device in each
pocket, a single valve controlling the mouths
of the several pockets, an electric circuit,
50 and a switch operatively connected with the
valve-operating means and arranged to close
the circuit to each sparking device when the
pocket containing such device is opened.

3. In an igniting device, in combination, a
55 combustion chamber, a valve casing having
a fluid induction port and lateral pockets, a
valve seated in the casing and having an
axial port open to the combustion chamber,
and a lateral port open to the induction port
60 and openable in alternation to the pockets,
and an electric sparking device in each
pocket.

4. In combination, a combustion chamber,
sparking terminals for igniting gas within
65 said chamber, means for exposing said ter-

minals to gas in said chamber and for com-
pletely housing said terminals as desired, a
stem for operating said means, and an elec-
trical switch mounted on said stem and plac-
ing the sparking terminals in circuit upon
70 exposure thereof.

5. An igniting device for an explosion
engine, comprising a single piece adapted
75 to be connected with the combustion cham-
ber of such an engine and having a plurality
of sets of sparking terminals, means carried
by said piece for exposing or isolating any
one of the sets of sparking terminals as de-
sired, and a switch mounted on said means
for completing a circuit through each set of
80 terminals upon exposure thereof.

6. An igniting device for an explosion
engine, comprising a single piece adapted to
be connected with the combustion chamber
85 of such an engine and having a plurality of
pockets, a plurality of separately-removable
spark-plugs carried by said device and hav-
ing sets of sparking terminals one set being
housed in each said pocket, means also car-
ried by said piece for exposing or isolating
90 any one of said pockets, and a switch mount-
ed on said means for completing a circuit
through each set of terminals upon ex-
posure thereof.

7. In combination with a cylinder for an
internal combustion engine, a plurality of
igniting devices mounted in stationary rela-
tion with respect to said cylinder, means
establishing communication from the re-
spective igniting devices to the cylinder, a
100 shut-off means controlling such communica-
tion to alternatively place the igniting de-
vices in communication with the cylinder,
an operating circuit, a switch means me-
chanically connected to said shut-off means
105 and controlling such operating circuit for
establishing operating connection to the ig-
nition device which is in communication
with the cylinder and simultaneously break-
ing the operating connection to the other
110 igniting device which is not in communica-
tion with the cylinder.

8. In combination with a cylinder of an
internal combustion engine, a plurality of
stationary igniting devices, means providing
115 communication between said igniting devices
and the cylinder, means for shutting off
communication from either igniting device
to the engine, a switch connected to and op-
erated with said shut-off means, and an
operating circuit connected to said switch
120 to be placed thereby in connection with the
igniting device which is in communica-
tion with the engine.

9. In combination, a combustion chamber,
sparking elements for igniting gas within
said chamber, means for exposing said ele-
ments to the gas in said chamber and for
completely housing the said elements as de-
sired, a stem for operating said means, and
130

an electric switch operated by the stem for placing the elements in circuit exposure thereof.

10. In an igniting device, in combination, a combustion chamber, a plurality of electric sparking devices, and unitary means for successively exposing the sparking devices to the chamber and bringing them in electrical

action, and for cutting them off from communication with the chamber and throwing them out of electrical action.
